SELF-ADJUSTING WRENCH

Clarence B. Lober, United States Army,
Dayton, Ohio

Application September 3, 1947, Serial No. 771,961

2 Claims. (Cl. 81—95)

(Granted under the act of March 3, 1883, as
amended April 30, 1928; 370 O. G. 757)

1

The invention described herein, if patented, may be manufactured and used by or for the Government for governmental purposes without the payment to me of any royalty thereon.

This invention relates to wrenches generally, and its primary object is to provide a wrench having a novel camming action in its gripping mechanism so as to produce a maximum mechanical advantage.

Another object of the invention consists in the provision of a wrench which is capable of efficient use in the gripping of screw caps for bottles and jars, as well as in the gripping of nuts, pipes, etc.

A still further object of the invention resides in the provision of a wrench which though especially constructed for use in connection with nuts may be equally useful as a pipe wrench by the mere removal of one of its parts.

Other objects and advantages of the invention will be apparent from the following description taken in connection with the accompanying drawings, in which

Figure 1 is a plan view of one form of the novel wrench;

Figure 2 is a side elevational view thereof;

Figure 3 is a perspective view of one of the jaws and its spacing member;

Figure 4 is a side elevational view of a modified construction of the wrench;

Figure 5 is an inverted plan view, partly in section, of the wrench shown in Figure 4;

Figure 6 is a fragmentary detail view, partly in section, of a still further modified construction; and

Figure 7 is a sectional view of a wrench embodying the pivotal construction shown in Figure 6.

Referring to the drawings in more detail, the numeral 1 indicates an elongated rigid bar adapted to serve not only as a handle for the wrench but also to support the clamping members. Pivoted to the end of the bar remote from the handle, which is indicated by the numeral 2, is a jaw 3 which is secured to the bar by means of a pivot pin 4. A spacing plate 5 is also mounted on the pin 4 between the jaw 3 and the body of the bar, and serves to space the jaw from the bar. This jaw, as well as others described herein, may be provided with the usual teeth to bite into the material being operated upon.

Also pivoted to the bar 1, intermediate its ends, in a second clamping member or jaw indicated by the numeral 6 and here shown as of circular or disc form. This disc is eccentrically mounted

on the bar 1 by means of a pivot pin 7, and has its periphery serrated as indicated by the numeral 8 for the purpose of providing the necessary biting action into the jar closure or other element to be gripped by the wrench.

The pivot 7 is so spaced from the jaw 3 as to provide the necessary cooperation between the disc and the jaw 3, and it will be noted that the diameter of the disc 6 is such that it will clear the jaw 3 if the disc should be swung to either side of the bar 1, and hence the wrench may be readily used for gripping purposes with the main body of the disc 6 on either side of the bar.

This arrangement of a pivoted jaw 3 and the eccentrically pivoted disc provides a camming action when the wrench is applied to a jar closure or other article to be turned, and consequently the gripping action is increased as the turning moment applied to the handle increases, thereby providing a decided mechanical advantage in the operation of the wrench.

In the modified construction shown in Figures 4 and 5, the advantages of the eccentrically mounted disc are also included but the construction is altered so as to permit the wrench to be used in connection with the screwing and unscrewing of nuts and also for cooperation with round articles such as pipes, etc., by the mere removal of one of the elements. In this construction the bar is indicated by the numeral 10, and is provided with a handle 11 at one end and a hook formation 12 on its opposite end. To the end 12 a jaw 13 is pivotally mounted by means of a pin 14, and in this construction the end of the bar is provided with an elongated slot to provide prongs between which the jaw 13 is pivoted as well as the other gripping element of this modified form of the construction. This other gripping element, namely, the pair of discs 15, held in spaced relation by a spacer 15', is eccentrically mounted within the slot of the bar 10 by means of a pivot pin or rivet 16. Disposed between the discs 15 is an arm 17 provided with an elongated slot 18 through which the pin 16 extends. On the free end of the arm 17 a jaw 19 is pivoted as by means of pin 20, and this jaw is intended to cooperate with jaw 13 in gripping an article. To this end the jaw 19 is disposed in the planes of the discs 15 so as to be cammed thereby into a progressively tighter contact with the nut or the like as the wrench is applied thereto. This movement of the jaw 19 toward and from the article being operated on is permitted by the pivotal and sliding connection of the arm 17 about the pin 16 provided by the slot 18. Should

it be desired to use this wrench as a pipe wrench or the like, it is only necessary that the arm 17 with its attached jaw 19 be withdrawn from about the pin 16, thereby permitting direct contact of the edges of the discs 15 with the pipe or the like so as to cooperate with the jaw 13. This construction as heretofore mentioned provides all the advantages of the wrench shown in Figures 1 and 2, but additionally provides for use in the screwing and unscrewing of nuts by the simple addition of a single element and without the use of any separate attaching means.

In the modified construction shown in Figures 6 and 7 a floating pivot is provided for the clamping disc, and it will be understood, of course, that this floating pivot may be incorporated in either of the previously described forms of the invention. In this form of the invention the bar is indicated by the numeral 30, and is provided with a handle 31 at one end and a jaw 32 at its opposite end. The jaw 32 is pivoted to the bar by means of a pivot pin 33 and is spaced therefrom by a spacing plate 34 also mounted on the pin 33. This part of the construction is identical with that shown in Figure 1, but obviously the jaw of Figures 4 and 5 could be equally well incorporated in this particular construction.

The bar 30 is provided with a slot 35 extending longitudinally thereof, and through which extends a pivot pin 36 on which the clamping disc 37 is eccentrically mounted. Within the slot 35 is a compression spring or other resilient element 38, one end of which bears against a side of the pivot pin 36 and the other end against the opposite end of the slot 35, thereby biasing the pin 36 and the disc 37 toward the jaw 32, thereby insuring contact of the disc with the object operated upon. To maintain the spring 38 within its slot 35, washers 39 are mounted on the pin 36, one on each side of the bar 30 so as to completely enclose the spring. This construction provides a floating pivot for the clamping disc 37, and thus enhances its gripping action in the cooperation with the opposite jaw of the wrench.

From the foregoing description, considered in connection with the attached drawings, it will be apparent to those skilled in the art that I have devised a wrench of relatively few parts of simple construction; that the wrench is so constructed

as to provide a progressively increasing grip upon articles to which it is applied by reason of the camming action of the eccentrically mounted disc, and that by reason of the removably mounted arm and its attached jaw the wrench may be readily converted from a pipe wrench to a wrench suitable for the application or removal of nuts of various types and contours, and vice versa.

There have been described herein what I now consider to be the preferred forms of the invention, but minor structural details may obviously be altered within the scope of the invention, and it is intended that all such changes be included within the scope of the appended claims.

I claim:

1. A wrench comprising a bar formed at one end to provide a handle, a jaw mounted on the opposite end of the bar, a serrated disc, a slot in the bar, a pivot pin eccentrically mounted on the disc and extending through said slot, and resilient means in the slot for biasing the pin and disc toward said jaw.
2. A wrench comprising a bar formed at one end to provide a handle, a jaw mounted on the opposite end of the bar, a serrated disc, a slot in the bar, a pivot pin eccentrically mounted on the disc and extending through said slot, resilient means in the slot for biasing the pin and disc toward said jaw, and washers on the pin on opposite sides of the bar for retaining the resilient means within the slot.

CLARENCE B. LOBER.
